(57) **CLAIM**

The ornamental design for a clip watch, as shown and described.

DESCRIPTION

FIG. 1 is a right front perspective view of a clip watch showing my new design;

FIG. 2 is a front elevational view of the clip watch of FIG. 1;

FIG. 3 is a right elevational view of the clip watch of FIG. 1;

FIG. 4 is a left elevational view of the clip watch of FIG. 1;

FIG. 5 is a rear elevational view of the clip watch of FIG. 1;

FIG. 6 is a top plan view of the clip watch of FIG. 1;

FIG. 7 is a bottom plan view of the clip watch of FIG. 1; and,

FIG. 8 is a right perspective view of the clip watch of FIG. 1 further illustrating the toothed latch in an open position.

The broken lines (and areas defined thereby) shown in the figures are for illustrative purposes only and form no part of the claimed design.

1 Claim, 4 Drawing Sheets
